ATTORNEY.

UNITED STATES PATENT OFFICE.

LEONARD L. LUDWIG, OF DELAVAN, KANSAS.

ELEVATING MECHANISM.

Application filed January 28, 1924. Serial No. 688,921.

To all whom it may concern:

Be it known that I, LEONARD L. LUDWIG, a citizen of the United States, residing at Delavan, in the county of Morris and State 5 of Kansas, have invented new and useful Improvements in Elevating Mechanism, of which the following is a specification.

The invention relates to improvements in elevating mechanism and particularly to 10 devices for handling coal and the like wherein the materials is first dumped into a hopper that is disposed in a pit and elevated therefrom and deposited in a bin or receptacle.

In the above installations it is desirable 15 that the pit shall be as shallow as possible in order to avoid excessive excavation in its formation as well as to obviate the removal of excessive storm water from it in use, it being obvious that the greater the depth of 20 the pit the greater will be its cost of construction and the greater will be the accumulation of water in it.

The chief object of my invention is to 25 provide a novel form of elevating member or bucket by which the above disadvantages are largely minimized.

Another object is to provide the bucket 30 with novel means for automatically closing its feed opening and another object is to provide novel means for automatically 35 operating the gate which controls the discharge opening of the hopper.

The invention is accomplished by the 40 mechanisms hereinafter described and illustrated in the accompanying drawings.

In the drawings, which illustrate one embodiment of the invention; Figure 1 is a side elevational view of the mechanism, the 45 hopper being shown in section; Fig. 2 a front elevational view of the same and Fig. 3 a side elevational view of the bucket in dumping position.

Referring to the drawings, 1 designates 50 a portion of the walls and 2 the bottom of a pit formed in the ground. The hopper 3 is suspended in the pit with each side inclined downwardly and inwardly toward the discharge opening 4 that is preferably formed in one of its sides adjacent the bottom thereof. A gate 5 is hinged upon 55 opposite sides of the hopper adjacent the opening 4 and is adapted to be swung upwardly and downwardly to close and expose the opening 4. The gate is composed of two end plates 6 that are pivoted at their free ends to the hopper walls and a trans-

versely curved or concaved plate 7 connected to the other ends of the end plates 6. A flange 8 extends along the upper edge of the curved plate 7 and projects forwardly therefrom to form an apron on the gate for preventing spilling of the material as it flows from the hopper when the opening 4 is exposed as shown in full lines in Fig. 1. At opposite ends of this 60 apron are formed the fingers 9 which are below the apron and project forwardly from the gate at a suitable angle with respect to the apron. The hubs 10 of the gate and the pivots 11 therefor are constructed so that 65 the springs 12 coiled on the pivots exert a friction on the gate in order that the gate will remain in any position to which it may be moved.

Guides 13 are suitably supported in front 70 of the discharge opening 4 of the hopper and lead from the bottom of the pit to the point where the material in the hopper is to be delivered.

The guides are turned toward the hopper 75 as they approach the bottom of the pit so that they will pass more or less under the inclined outer face of the hopper. The lower end of the inner member 13^a of each guide is curved upwardly rather sharply to form 80 a cam 14 the function of which will be explained hereafter.

A bucket 15 is supported on the guides 13 by the rollers 16 which are revolvably mounted at the forward four corners of the bucket. 90 The bucket is preferably a parallelogram in side outline so that its inner inclined wall 17 will pass under the discharge opening 4 of the hopper. The top of the bucket is open and a cable 18 is secured to the bucket in suitable manner, as to a cross member 19, that is secured at its opposite ends to the side walls of the bucket. The cable leads from a suitable hoisting mechanism by which the bucket is elevated and lowered on the 95 guides. The wall 17 does not extend upwardly to the top of the bucket but is short thereof to form a feed opening 20 in said side of the bucket.

A gate 21 controls the feed opening 20. 105 This gate is curved or concaved transversely and its end wings 22 are pivoted to the inner face of the opposite sides of the bucket. The pivots 23 are secured to the wings and project through said sides and levers 24 are secured 110 to the projecting ends of the pivots respectively. The levers extend in proper direc-

tion so that the rollers 25 mounted in their outer ends will ride in the guides 13. As the bucket ascends the rollers 25 follow the cam portions 14 of the guide members 13^a and the levers 24 are depressed forwardly, thereby causing the gate to rise rapidly at first and then slowly. The tilting movement of the levers is continued by the cam until the gate is fully closed. The gate then 10 remains closed since the rollers continuously engage the guide members 13^a during the ascent and descent of the bucket. In the descent of the bucket when the rollers 25 reach the cams 14 the gate is released and 15 gravity acts on the gate to cause it to descend and expose the feed opening in the bucket.

At the upper edge of the gate 21 is revolvably mounted a roller 26 which is so 20 disposed on the gate that as the latter rises it will abut the lower face of the apron 8 of the gate 5 and cause the latter gate to rise and cut off the flow of material from the hopper. It is apparent that the ends of the 25 fingers 9, as the gate 5 is closed, will tend to pass into the bucket, hence notches 27 are formed in the upper edge of the gate 21 to permit of this movement of the fingers. Eventually the roller 26 will clear the apron 30 8 but by this time both gates 5 and 21 are closed, and the fingers 9 are now in the path of the roller 26 when the bucket descends and the gate 5 is thereby opened.

When the gate 5 is open the end flanges 6 35 thereof cause the gate to be a chute, and the apron 8 spans the gap between the edge of the gate and the bucket so that none of the material being fed from the hopper drops into the pit.

As the gate 21 is caused to rise rapidly the 40 gate 5 is closed rapidly and the material cut off by the gate 5 and exterior thereof is bound to fall into the bucket.

As the gate 21 rises the material in the 45 bucket will tend to slide into the triangular portion 28 thereof that is behind the gate when the latter is in open position. Hence there is no spilling of the material through the feed opening in the bucket as the gate 50 21 rises.

The bottom 29 of the bucket is hinged at 55 30 to the wall 17 for outward movement. A bracket 31 is secured to the opposite or front edge of the bottom and carries a roller 32 at its outer end which rides on a rail 33 suitably fixed between the guides 13. The free end of the bracket is inclined upwardly sufficiently to cause the bottom to be closed by the cooperating roller and rail. 60 At the point where the bucket is to be dumped the rail 33 is curved outwardly or away from the bucket so that the roller will follow the curvature of the rail under the influence of the bottom which supports the 65 material in the bucket. The bottom there-

fore comes to rest while the bucket proper continues its ascent for a short distance. The bottom has upstanding wings 34 at its side edges to cause the same to be a chute to conduct the material from the bucket 70 into the container intended to receive it.

It is now apparent, since the bucket is angular in shape and its wall facing the hopper is inclined inwardly and the feed opening is formed in that side, that the 75 bucket requires much less space beneath the discharge opening of the hopper than where the entire bucket is placed beneath said discharge opening as in other prior mechanism. Hence a large saving is made 80 in the depth of the pit.

At the same time the feed controlling gate of the hopper being opened and closed by the feed controlling gate of the bucket 85 the material in the hopper will not flow from it except when the bucket is in proper position and condition to receive it. By causing the bucket hoisting mechanism to be automatically timed in its operation the 90 entire mechanism may be automatic in operation.

What I claim is:

1. In mechanism of the class described, a 95 hopper having a discharge opening in a wall thereof, pivotally mounted means for controlling the said opening, a bucket adapted to be moved upwardly and downwardly in front of said opening, the bucket having an inclined wall facing the hopper and having a feed opening therein, the said wall being adapted to permit a portion of the bucket to pass under the discharge opening in the hopper, means in the bucket for controlling the feed opening and means responsive to the movements of the bucket for operating 100 the controlling means in the bucket and cause the hopper controlling means to operate simultaneously therewith.

2. In mechanism of the class described, a 110 hopper having a discharge opening in a wall thereof, a pivotally mounted gate for controlling the said opening, a bucket adapted to be moved upwardly and downwardly and having an inclined wall opposing the hopper and adapted to pass substantially under the hopper, the said wall having a feed opening therein, a gate pivotally mounted on the bucket for controlling the feed opening and adapted to engage the controlling gate of the hopper for opening 120 and closing the latter, and means to guide the bucket in its movements and adapted to cause its controlling gate to be opened and closed at selected times to cause the hopper gate to open and close simultaneously therewith.

3. In mechanism of the class described, a 125 hopper having a discharge opening in a wall thereof, means pivotally mounted to expose and close the said opening and when 130

open forming a chute for the hopper, a bucket adapted to be moved upwardly and downwardly in front of the hopper, the wall of the bucket opposing the hopper having 5 a feed opening therein, said wall being inclined to permit a portion of the bucket to pass beneath the discharge opening, a gate pivotally mounted on the bucket for controlling the feed opening and adapted to open 10 and close the chute, guides to control the movements of the bucket and means connected to the latter gate and engaging the guides for opening and closing said gate as the bucket is moved to cause the chute to 15 automatically enter and pass from the feed opening.

4. In mechanism of the class described, a hopper having a discharge opening in a wall thereof through which material in the hopper will flow by gravity, a chute pivotally mounted on the hopper for exposing and closing the discharge opening, fixed guides in front of the hopper, a bucket adapted to be moved upwardly and downwardly on the 20 guides and having an inclined wall opposing the hopper adapted to permit a portion of the bucket to pass under the hopper and its discharge opening, the said inclined wall having a feed opening 25 therein, a gate pivotally mounted on the bucket for exposing and closing the feed opening and adapted to open and close the chute, for controlling the flow of material from the hopper into the bucket, cams on the 30 guide members, and levers rigidly connected to the gate having movable engagement with the guides and adapted to be actuated by 35 the cams for operating the gate at selected points of time.

40 5. In a mechanism of the class described, a hopper having a discharge opening, means for controlling said opening, a bucket adapted to be moved under said opening, a feed opening in said bucket, means for controlling said feed opening and means responsive to the movement of the bucket for operating the controlling means for the bucket feed opening and for causing the hopper discharge opening controlling means to operate simultaneously therewith.

6. In a mechanism of the class described, a hopper having a discharge opening, means for controlling said opening, a bucket adapted to be moved under said opening, a feed opening in said bucket, means for controlling said feed opening and means to guide the bucket in its movement and adapted to cause the controlling means for the bucket feed opening to operate and to cause the controlling means for the hopper discharge 55 opening to operate simultaneously therewith. 60

7. In a mechanism of the class described, a hopper having a discharge opening, means for controlling said opening, a bucket adapted to be moved under said opening, a feed 65 opening in said bucket, a gate for controlling said feed opening and adapted to engage the controlling means for the hopper discharge opening for simultaneously operating it, and means responsive to the movement of the bucket for operating the gate. 70

8. In a mechanism of the class described, a hopper having a discharge opening, means to control said opening, a bucket adapted to be moved under said opening, a feed opening in the bucket, a gate to control the feed opening and adapted to simultaneously operate the controlling means for the hopper discharge opening, a guide to control the movement of the bucket and means having 75 a connection to the gate and engaging the guide for operating the gate. 80

9. In a mechanism of the class described, a hopper having a discharge opening, a member pivoted to the hopper for controlling said opening, a bucket adapted to be moved under the said opening, a feed opening in the bucket, a gate to control said feed opening and adapted to engage the pivoted member for operating it simultaneously 85 with the operation of said gate, a guide to control the movement of the bucket and means mounted on the bucket and connected to the gate and movably engaging the guide for operating the gate. 90 95

In witness whereof I have hereunto subscribed my name this 21st day of January, 1924.

LEONARD L. LUDWIG.
